Primary Examiner — Jeffrey D Asch*Assistant Examiner* — Rebekah A Caruso(74) *Attorney, Agent, or Firm* — Cantor Colburn LLP(57) **CLAIM**

The ornamental design for a wireless communication repeater, as shown and described.

DESCRIPTION

FIG. 1 is a perspective view of a wireless communication repeater, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines illustrating portions of the wireless communication repeater form no part of the claimed design.

The dot-dot-dash lines in the figures illustrate a boundary of the claimed design and form no part of the claimed design.
